GLOVELET

Maureen A. Horne, Denver, Colo.

Application March 30, 1955, Serial No. 35,278

Term of patent 3½ years

(Cl. D3—11)

Fig. 1 is a front perspective view of a glovelet showing my new design;

Fig. 2 is a rear perspective view thereof; and

Fig. 3 is a plan view thereof.

The dotted line disclosure of a hand in Figs. 1 and 2 of the drawing is for convenience of illustration only.

I claim:

The ornamental design for a glovelet, as shown and described.
